WICK TYPE VAPORIZER

Delbert S. Raleigh, Reno, Nev.

Application June 6, 1950, Serial No. 166,461

7 Claims. (Cl. 299—20)

1

This invention relates to a vaporizer of the wick type. It may be used for the controlled evaporation of disinfectants and deodorizers into the surrounding atmosphere to purify the air.

The wick type of vaporizer that has recently become popular has brought with it several problems. For one thing the containers have tended to fall over too easily and have spilled the fluid onto furniture, rugs, etc. The fluid has also been spilled when the wicks have been pulled out too far. Furthermore, the containers themselves have been relatively unattractive, and their advertising matter and labels have made them unsightly.

The present invention provides an attractive, refillable vaporizer that may be used with any of the well-known fluid deodorants and disinfectants now on the market. It includes a hollow, open-top container, and a hollow open-bottom piston member that fits into the open upper end of the container to close the container. The wick is supported over the outer wall surface of the piston member, preferably being secured to the upper end thereof just below the top. The lower end of the wick is secured to the bottom of the interior of the hollow container base. The thickness of the wick is such that it fills the space between the walls of the telescoping members. Since the wick fits snugly within the container, it will hold itself and the piston member at any desired height to expose as much wick as is necessary to dispense the volatile liquid at the desired rate.

The invention will be better understood from the following detailed description of a preferred embodiment. It will be understood that there may be changes in shape, materials, and elements which will still fall within the scope of the invention as defined in the appended claims. The description and the drawings are presented in accordance with United States Revised Statutes, section 4888, and are illustrative of the invention, not definitive of it.

In the drawings:

Fig. 1 is a view in perspective of a vaporizer embodying the principles of the invention, the wick being shown in an intermediate dispensing position.

Fig. 2 is a view in elevation and partly in section of the vaporizer of Fig. 1, showing it in its closed inoperative position.

Fig. 3 is a view in elevation and in section showing the vaporizer in its fully extended position when it is disseminating the vapor into the atmosphere at the maximum rate and

Fig. 4 is a top plan view of the vaporizer with the cap in position so that the air and filler opening therethrough is closed.

The vaporizer shown in Figs. 1 to 4 is cylindrical, and this is the preferred shape. However,

2

it may be made in various other shapes, if desired. For example, it may be elliptical or square as seen in cross section.

The lower or base member of the vaporizer is a hollow open-topped, walled cylindrical container 10 having a flanged base 11. The container 10 supports the device and its wide base keeps it from being knocked over accidentally. The inner wall 12 of the container 10 is preferably cylindrical and provides a chamber 13 that holds the volatile liquid.

A ring 14 may be cemented or otherwise formed at the bottom 15 of the chamber 13. The lower end 19 of a wick 20 is cemented or otherwise secured adjacent to the lower end 15 of the chamber 13, being shown here as held between the ring 14 and container wall 12. The lower portion 21 of the wick 20 preferably comprises a plurality of vertical threads, without any cross threads, so that it consumes less space. The upper portion 22 of the wick 20 is woven with horizontal cross threads, as well as the vertical threads, and its upper end 23 is secured by cement or otherwise to the upper end 24 of a cylindrical piston 25 between the piston and an outer ring 26.

The cylindrical piston 25 supports the wick 20 on its outer wall surface 27, the clearance between the wall 27 and the wall 12 of the container being approximately the thickness of the wick 20, so that when the piston 25 is raised or lowered to expose more or less of the wick 20, the friction present will support the piston at whatever height it is moved to. The wick 20 is secured at both ends 19 and 23 and is longer between these points than the vertical length of the wall 12 and is shorter than the combined vertical lengths of the wall 12 and wall 27 so that the top member cannot be pulled all the way out of the container 10. The piston 25 is hollow and has a relatively thin wall so as not to cut down on the liquid capacity of the base 10 or to interfere with the lower end 21 of the wick 20 folding in when the dispenser is closed, as in Fig. 2.

At the upper end 24 of the top member 25 a valve is provided. It is illustrated as a lower cap 30 and an upper cap 31. The lower cap 30 may be made integrally with or cemented to the piston 25. It has a central threaded opening 32 that receives a threaded nipple 33 secured on the lower surface of the upper cap 31. The threaded opening 32 is preferably large enough so that the dispenser can be filled with liquid therethrough, when the upper cap 31 is unscrewed. It may also be filled thru the valve openings 35, 36.

In order to admit air to the chambers 13 and 28 when the piston 25 is lifted in relation to the base and to exhaust air therefrom when the piston is telescoped, two alignable openings 35, 36

are provided through the caps 30 and 31 respectively. The openings 35, 36 preferably are the same size and lie at the same radial position so they may be aligned and disaligned by turning the upper cap 31. When disaligned, they close the vaporizer and prevent evaporation.

All the parts except the wick may be made from well-known present day plastic materials. The plastic used for the case may be transparent to show the height of the liquid or it may be opaque to conceal the liquid and the interior of the device. The utility of such a vaporizer as that illustrated makes it suitable for use in an office or for a living room.

The wick 20 may be woven in the round or it may be seamed together to form a tubular element. The cross threads may be removed for the lower portion 21, or the wick 20 may be woven without any threads for that portion.

When the device is not in use, the piston 25 will be in its lowest position, as shown in Fig. 2, and the upper part 22 of the wick 20 will rest between the piston's wall 26 and the container wall 12. The vertical threads of the lower part 21 of the wick 20 will fold inside the hollow piston chamber 28. The upper cap 31 will normally be turned to the closed position shown in Figs. 3 and 4, with the holes 35 and 36 out of alignment to keep the volatile liquid from evaporating.

When it is desired to dispense some of the deodorant or disinfectant into the room, the cap 31 is turned so that the valve openings 35 and 36 are aligned, as shown in Fig. 2. Then the cap 30 is lifted until the wick 20 and piston 25 are pulled up as high as desired (which may be part of the way up as in Fig. 1, or all the way up as in Fig. 3). The cap 31 is again turned to disalign the holes 35 and 36 as shown in Figs. 3 and 4. The snug fit of the wick 20, backed up by the piston 15, will hold it in this position and the closing of the air column by disaligning of the holes 35 and 36 also helps it remain fixed. When the air has been purified the cap 31 is again turned to align the holes 35 and 36; the piston 25 and wick 20 are then depressed by pushing down on the cap 31, and after the container is closed the holes 35 and 36 are again disaligned.

I claim:

1. A wick-type vaporizer having a hollow open-topped, walled base member; a hollow open-bottomed, walled top member loosely fitted to telescope within said base member; a tubular wick fitted between the walls of said telescoped members, secured at its upper end to said top member and at its lower end to said base member, said wick between its secured ends being longer than the vertical wall length of said top member and shorter than the combined vertical wall lengths of said base and said top members, whereby when said base and top members are vertically extended said wick will limit their relative movement, and when said members are telescoped, the surplus length of wick will be accommodated within said hollow members.

2. The device of claim 1 in which there is a valve in said top member to allow free flow of fluids into or out of the chamber formed by said telescoped base and top members.

3. A vaporizer of the wick type including in combination a hollow container having a supporting base and an open upper end; a hollow piston member of the same exterior shape as the inte-

rior shape of said container adapted to slide up and down within said container with clearance between their respective walls; a wick of a thickness approximately equal to said clearance, embracing said piston member and secured to said piston at its upper end, and extending down beyond the lower end of said piston into said container and having its lower end secured adjacent the lower end of said container near said base member; and a closure member secured to the upper end of said piston member.

4. The vaporizer of claim 3 in which only the vertical threads of the wick extend below the piston member.

5. A vaporizer of the wick type including in combination a hollow container having a supporting base and an open upper end; a hollow piston member of the same exterior shape as the interior shape of said container, adapted to slide up and down within said container with clearance between their respective walls; a wick of a thickness approximately equal to said clearance, embracing said piston member and secured to said piston at its upper end, and extending down below the lower end of said piston into said container; and a closure member comprising two cap portions, pivotally secured to each other; said caps having vertical openings therethrough lying the same radial distance from the center so that said openings may be aligned or disaligned.

6. A wick-type vaporizer having a hollow open-topped walled base member; a hollow open-bottomed walled top member loosely fitted to telescope within said base member; a tubular wick fitted between the walls of said telescoped members and thick enough to hold them without slipping in any relative location in which they are positioned until they are repositioned, said wick being secured at its upper end to said top member, said wick between its secured ends being longer than the vertical wall length of said top member.

7. A vaporizer of the wick type including in combination a hollow container having a supporting base and an open upper end; a hollow piston member of the same exterior shape as the interior shape of said container, adapted to slide up and down within said container with clearance between their respective walls; a wick embracing said piston member and secured to said piston member adjacent its upper end, said wick having a thickness approximately equal to said clearance so as to hold said piston at any vertical height to which it may be set with regard to said container, by frictional contact with the said walls, until said piston member is repositioned, said wick extending down beyond the lower end of said piston into said container; and a closure member secured to the upper end of said piston member.
